(57) **CLAIM**

The ornamental design for a painting device, as shown.

DESCRIPTION

FIG. 1 is a perspective view of a painting device according to the invention;

FIG. 2 is a front elevation view of the painting device depicted in FIG. 1;

FIG. 3 is a rear elevation view of the painting device depicted in FIG. 1.

FIG. 4 is a side elevation view of the painting device depicted in FIG. 1;

FIG. 5 is an opposing side elevation view of the painting device depicted in FIG. 1;

FIG. 6 is a bottom plan view of the painting device depicted in FIG. 1;

FIG. 7 is a top plan view of the painting device depicted in FIG. 1; and,

FIG. 8 is an exploded perspective view of the painting device depicted in FIG. 1.
